CIRCUIT ARRANGEMENT FOR THE FREQUENCY MODULATION OF A CARRIER WAVE

Gerard Hepp, Eindhoven, Netherlands, assignor, by mesne assignments, to Hartford National Bank and Trust Company, Hartford, Conn., as trustee.

Application April 27, 1946, Serial No. 665,389
In the Netherlands June 30, 1942

Section 1, Public Law 690, August 8, 1946
Patent expires June 30, 1962

7 Claims. (Cl. 332—18)

1

For modulating the frequency of carrier waves generated by a high-frequency oscillator it is known to use a so-called reactance tube whose mutual conductance is governed by the modulating oscillation. It is naturally desirable that the frequency deviations should vary linearly with the modulation voltages and, if a reactance tube is used in the known manner, this will generally only be the case within a limited zone of the control range of the tube and, if operating and bias voltages are carefully chosen, to a satisfactory approximation. If, when in use, the tube is subjected to variations in the course of time, as is always the case, the quality of the modulation is more and more affected so that readjustment is repeatedly necessary.

According to the invention, these disadvantages are obviated by the use of anode modulation instead of mutual conductance modulation in the reactance tube.

In order that the invention may be clearly understood and readily carried in effect it will now be described more fully with reference to the accompanying drawing, forming a part of the specification and in which

Fig. 1 is a schematic diagram of a modulation circuit arrangement according to the invention,

Fig. 2 is a schematic diagram of another embodiment of the modulation circuit arrangement according to the invention, and

Fig. 3 is a further embodiment of a modulation circuit arrangement according to the invention.

Referring to Fig. 1, the anode circuit of a self-oscillating oscillator valve 1 includes a tuned circuit 2, 3 which determines the mean frequency. A small condenser 5 couples the anode circuit of valve 1 to the control grid of a reactance valve 6. The resistance 7 connects the said control grid to the cathode of the valve 6. Due to the fact that the impedance of the condenser 5 is large compared with the resistance 7 the grid voltage of the valve 6 will lead the anode voltage of the oscillator valve 1 by about 90°, as will also be the case with the current supplied from the reactance valve. This current passes through two series-connected coils 8 and 9 and through the secondary coil of a transformer 10, on the primary coil of which the modulation voltages are impressed. The coil 8 is coupled to a coil 11 included in the anode circuit of the valve 1 and the coil 9 is coupled to the coil 2 of the tuning circuit 2, 3, the couplings being so chosen that voltage from the oscillator valve 1 practically does not reach the anode circuit of the

2

modulation valve 6 and the anode circuit of the oscillator valve 1 is not directly influenced by the modulating voltage. In operation, the anode current of the reactance valve 6 which leads the anode voltage of the valve 1 by 90° is modulated in amplitude by the modulating voltage which is impressed on the anode circuit of the valve 6 via transformer 10. These modulated currents are induced in the tuning circuit 2, 3, by the coil 9. Tuning circuit 2, 3 also has the unmodulated anode current of the oscillator valve 1 passing through it. This results in a variation in the frequency determined by the resonant circuit 2, 3 which varies linearly with the modulation voltages if the anode current of the valve 6 is modulated by these voltages in a sufficiently linear manner. For the very purpose of obtaining this effect it is desirable that care should be taken that no voltage from oscillator valve 1 is directly impressed on the circuit of the reactance valve 6.

A circuit arrangement which offers advantages in adjustability at higher frequencies is shown in Fig. 2.

In this embodiment, the reactance valve 6 which, as before, is modulated in its anode circuit is not connected directly in parallel with the tuning circuit 2, 3, of the generator valve 1 but a tube 12 is interposed between the tube 6 and tube 1. The grid of tube 12 is connected to the anode of the tube 6 by means of a blocking condenser 13. In this circuit arrangement care should be taken that the tube 12 has a sufficiently linear characteristic curve or else that the latter is straightened in known manner by feed-back coupling.

In the embodiment shown in Fig. 3, the modulation is effected by means of a diode 14 which acts as a limiter and whose threshold value is determined not only by a battery 15 but also by the modulation voltage to be applied between the terminals 16—16. The external circuit of the tube includes a circuit 17 which is tuned to the mean frequency and damped by a parallel resistance 18. The oscillations displaced in phase by 90° are supplied to the diode system through a resistance 19 and the modulated phase-displaced oscillations are applied, similarly to Fig. 2, to the control grid of a buffer valve 12.

The three circuit arrangements shown are all simplex. It is, however, possible without further precautions to use push-pull connected tubes in all three cases with similar attendant well-known advantages.

What I claim is:

55 1. A circuit arrangement for frequency mod-

ulating a carrier wave, comprising a carrier frequency oscillator circuit having a first electron discharge tube having an anode, a control grid and a cathode, a resonant circuit coupled to the anode of said first discharge tube to determine the central frequency of the oscillations produced by said oscillator circuit, a reactance tube circuit comprising a second electron discharge tube having an anode, a control grid and a cathode, means to couple said resonant circuit to the control grid of said second tube to apply a phase quadrature voltage thereto, means to apply operating potentials to said tubes, means to amplitude-modulate the anode potential of said reactance tube to produce amplitude-modulated oscillations substantially 90° out of phase with respect to the carrier frequency oscillations of said oscillator circuit, means to couple the output of said reactance tube circuit to said resonant circuit to combine the carrier frequency oscillations and the amplitude-modulated quadrature oscillations to produce a frequency-modulated carrier wave, and to couple the anode circuit of said first tube in opposition to the output circuit of said second tube effectively to isolate the anode of said first tube from the modulating potential applied to said reactance tube circuit.

2. A circuit arrangement for frequency modulating a carrier wave, comprising a carrier frequency oscillator circuit having a first electron discharge tube having an anode, a control grid and a cathode, a resonant circuit coupled to the anode of said first discharge tube to determine the central frequency of the oscillations produced by said oscillator circuit, a reactance tube circuit comprising a second electron discharge tube having an anode, a control grid and a cathode, a capacitor coupling said resonant circuit to the control grid of said second tube to apply a phase quadrature voltage thereto, means to apply operating potentials to said tube, means to amplitude-modulate the anode potential of said reactance tube to produce amplitude-modulated oscillations substantially 90° out of phase with respect to the carrier frequency oscillations of said oscillator circuit, means inductively coupling the output of said reactance tube circuit to said resonant circuit to combine the carrier frequency oscillations and the amplitude-modulated quadrature oscillations to produce a frequency-modulated carrier wave, and a transformer having the primary winding thereof connected in series with said inductive coupling means and the secondary connected in series with said resonant circuit to couple the anode circuit of said first tube in opposition to the output circuit of said second tube effectively to isolate the anode of said first tube from the modulating potential applied to said reactance tube circuit.

3. A circuit arrangement for frequency modulating a carrier wave, comprising a carrier frequency oscillator circuit having a first electron discharge tube having an anode, a control grid and a cathode, a resonant circuit coupled to the anode of said first discharge tube to determine the central frequency of the oscillations produced by said oscillator circuit, a reactance tube circuit comprising a second electron discharge tube having an anode, a control grid and a cathode, means to couple said resonant circuit to the control grid of said second tube to apply a phase quadrature voltage thereto, a third electron discharge tube having an input circuit and an output circuit, means to apply operating potentials to said tubes, means to amplitude-modulate the

anode potential of said second tube to produce amplitude-modulated oscillations substantially 90° out of phase with respect to the oscillations of said oscillator circuit, means to couple the anode of said second tube to the input circuit of said third tube, and means to couple the output circuit of said third tube to said resonant circuit to combine the carrier frequency oscillations and the modulated quadrature oscillations to produce a frequency modulated carrier wave.

4. A circuit arrangement for frequency modulating a carrier wave, comprising a carrier frequency oscillator circuit having a first electron discharge tube having an anode, a control grid and a cathode, a resonant circuit coupled to the anode of said first discharge tube to determine the central frequency of the oscillations produced by said oscillator circuit, a reactance tube circuit comprising a second electron discharge tube having an anode, a control grid and a cathode, a capacitor coupling said resonant circuit to the control grid of said second tube to apply a phase quadrature voltage thereto, a third electron discharge tube having an input circuit and an output circuit, means to apply operating potentials to said tubes, means to amplitude-modulate the anode potential of said second tube to produce amplitude-modulated oscillations substantially 90° out of phase with respect to the oscillations of said oscillator circuit, a second capacitor coupling the anode of said second tube to the input circuit of said third tube, and means to couple the output circuit of said third tube directly to said resonant circuit to combine the carrier frequency oscillations and the modulated quadrature oscillations to produce a frequency modulated carrier wave.

5. A circuit arrangement for frequency modulating a carrier wave, comprising a carrier frequency oscillator circuit having a first electron discharge tube having an anode, a control grid and a cathode, a first resonant circuit coupled to the anode of said first discharge tube to determine the central frequency of the oscillations produced by said oscillator circuit, a second electron discharge tube having an anode and a cathode, means coupling said resonant circuit to the anode of said second tube to apply a phase quadrature voltage thereto, a third electron discharge tube having an anode, a control grid and a cathode, a second resonant circuit tuned to said central frequency and coupled to the control grid of said third discharge tube, means to damp said second resonant circuit, means to apply operating potentials to said tubes, means to apply modulating potentials to said second discharge tube to produce amplitude-modulated oscillations in quadrature with the oscillations of said oscillator circuit, means to bias said second tube to limit the applied modulation potential to values above a predetermined value, means to couple the anode of said second tube to the control grid of said third tube, and means to couple the anode of said third tube to said first resonant circuit to combine the carrier frequency oscillations and said amplitude-modulated quadrature oscillations to produce a frequency-modulated carrier wave.

6. A circuit arrangement for frequency-modulating a carrier wave, comprising a carrier frequency oscillator circuit having a first electron discharge tube having an anode, a control grid and a cathode, a first resonant circuit coupled to the anode of said first discharge tube to determine the central frequency of the oscillations produced by said oscillator circuit, a second elec-

tron discharge tube having an anode and a cathode, a first capacitor coupling said resonant circuit to the anode of said second tube to apply a phase quadrature voltage thereto, a third electron discharge tube having an anode, a control grid and a cathode, a second resonant circuit tuned to said central frequency and coupled to the control grid of said third discharge tube, a resistor shunting said second resonant circuit, means to apply operating potentials to said tubes, means to apply modulating potentials to the cathode of said second discharge tube to produce amplitude-modulated oscillations in quadrature with the oscillations of said oscillator circuit at the anode of said second tube, means to bias said second tube to limit the applied modulation potential to values above a predetermined value, means to connect the anode of said second tube directly to the control grid of said third tube, and means to connect the anode of said third tube directly to said first resonant circuit to combine the carrier frequency oscillations and said amplitude-modulated quadrature oscillations to produce a frequency-modulated carrier wave.

7. A circuit arrangement for frequency-modulating a carrier wave comprising means including an oscillator electron discharge tube having an

15

20

25

anode and a circuit therefor to generate a first oscillation of carrier wave frequency, a reactance electron discharge tube to produce a second oscillation of carrier wave frequency in phase quadrature with said first oscillation, means coupled to said reactance tube to amplitude modulate said second oscillation in accordance with a signal, isolation means for decoupling the anode circuit of said oscillator tube from said amplitude modulation means to prevent direct amplitude modulation of said oscillator tube means, and means to combine said first and second oscillations to produce a frequency modulated carrier wave.
